DAVID A. WALLACE, OF DETROIT, MICHIGAN, ASSIGNOR TO CHRYSLER CORPORATION, OF DETROIT, MICHIGAN, A CORPORATION OF DELAWARE

METHOD OF MAKING AXLE HOUSINGS

Application filed October 1, 1930. Serial No. 485,677.

This invention relates to an improved axle housing and method of forming the same.

Heretofore, in order to form articles of irregular contour, such as rear axle housings of motor vehicles, from a planular blank of sheet metal, it has been necessary to stamp out blanks of irregular contour or to build separate pieces of stock onto a rectangular blank so as to provide sufficient material for the enlarged differential casing with which such axle housings are provided. In each case considerable labor is involved and large quantities of material are wasted.

The main objects of this invention are to provide a method for forming an axle housing from a single integral piece of sheet metal stock of irregular contour so as to obviate the waste of material involved in forming or building up irregular blanks; to provide a method for constructing a cylindrical sleeve and an integral, arcuate end portion which have axes that are normal to each other from a single piece of regular shaped stock; and to provide a method for constructing a differential casing and axle enclosing sleeve of substantially uniform thickness from a single integral piece of sheet material of substantially rectangular shape.

An illustrative embodiment of the invention is shown in the accompanying drawing, in which:

Fig. 1 is a plan view of a piece of stock or blank from which one section of an axle housing is formed by my improved method.

Fig. 2 is a plan view showing the blank as it appears after a shearing operation.

Fig. 3 is a side elevation showing the stock as it appears after the first die forming operation in which the sheared end of the stock is offset.

Fig. 4 is an end elevation of a partially formed axle housing at which stage the unsheared portion of the stock is channel shaped and the portions thereof adjacent the shear are spread apart substantially 90°.

Fig. 5 is an end elevation showing a partially formed housing as it appears after its unsheared end has been formed into a cylindrical sleeve.

Fig. 6 is a diagrammatic illustration, part-

ly in section, showing the die forming operation by which the differential casing is shaped.

Fig. 7 is a side elevation of an assembled axle housing.

Fig. 8 is a transverse section taken on the line 8—8 of Fig. 7.

In the form shown, a substantially rectangular piece of sheet metal material 1 of suitable thickness is sheared longitudinally at 2 along its central axis from one end to a position intermediate its ends. An aperture 3 is then formed at the inner extremity of the shear 2 as shown in Fig. 2. The shear 2 and the aperture 3 may, if desired, be formed in a single operation.

The sheared end portion of the stock is then bent into the shape shown in Fig. 3 by a die forming, or other suitable operation. During this step of the method the inner part 4 of the sheared end portion is struck downwardly at a slight inclination to the unsheared end along a transverse line 5 which is located substantially at the inner extremity of the shear 2, and the outer part of the sheared end portion is bent into a plane which is substantially parallel to the plane of the unsheared portion of the stock. The shear 2 divides the left end portion of the stock into two sections forming prongs 7 and 8 which are substantially equal in dimension to each other. The prongs 7 and 8 are preferably bent transversely into an arcuate shape, as illustrated in Figs. 3, 4 and 5, during the operation in which the offset is formed.

The unsheared portion 6 of the stock is bent into a channel shape, shown in Fig. 4, by suitable dies or other bending mechanism and during this operation the prongs 7 and 8 are spread apart substantially 90°. The channel shown in Fig. 4, is then formed into a cylindrical tube by bringing the edges of the channel together with the aid of suitable dies. At the end of this operation the article appears as illustrated in Fig. 5 and has a groove 9 between the edges which have been forced together. These edges are then welded along the groove 9, thus forming a substantial integral tubular sleeve 10 of cylindrical shape. The prongs 7 and 8 are

spread further apart during the sleeve forming operation and when the edges of the sides of the channel abut each other, the prongs are located on diametrically opposite sides 5 of the sleeve at substantially 180° apart.

The sleeve 10 forms an enclosure for the axle of a vehicle and the prongs 7 and 8 are shaped in the above manner so as to provide a half section of a casing for the differential with which the axle is connected. The sleeve 10 is received by the die parts 11 and 12 which are provided with registering recesses for receiving the prongs 7 and 8. The recesses of the die parts 11 and 12 have arcuate walls 13 and 14, respectively, against which the prongs 7 and 8 are pressed by a ram 15 having a substantially semi-cylindrical head 16. The thickness of the head 16 and the width of the recesses is less than 10 the width of the prongs 7 and 8, and thus when the housing is placed in the dies, the edges of the prongs protrude beyond the sides of the head and recesses. The ram 15 has an inclined outer extremity 17 against which 15 an actuating member 18 having a correspondingly inclined face 19 bears. When the member 18 is urged downwardly, the ram 15 is forced to the right as viewed in Fig. 6, thereby imparting to the prongs, the shape of the head 16 and of the walls 13 and 14 of the recesses. Those portions of the prongs 7 and 8, which protrude beyond the sides of the head 16 are bent substantially normal to the 20 portions of the prongs which are pressed against the arcuate walls 13 and 14, forming flanges 20 and 21 on the respectively opposite edges of the prongs.

Two housing sections of the type shown in Fig. 6 are assembled together in the manner 40 illustrated in Figs. 7 and 8 by placing the extremities of the enlarged semi-cylindrical ends of the sections in registration with each other and securing the same together by welding. A ring 22 is preferably placed adjacent 45 the flange 20 during assembling of the housing sections and is spot-welded in place so as to provide a reinforcement in the differential casing on the front side thereof. The flange 20 and reinforcement 22 is provided with 50 apertures 23 for receiving the bolts by which the rear bearing housing of the main drive shaft of a vehicle is secured to the differential casing. Split ring sections, not shown, 55 may be used for this purpose in place of an integral ring.

Although but one specific embodiment of this invention has herein been shown and described, it will be understood that various 60 changes in the size, shape and arrangement of parts may be made without departing from the spirit of my invention and it is not my intention to limit its scope other than by the terms of the appended claims.

What I claim is:

65 1. The method of manufacturing an axle

housing which consists in shearing a piece of metal stock at one end, forming an offset in the sheared end thereof, forming the unsheared portion of said stock into a tube, thereby placing the portions of said stock 70 adjacent said shear on diametrically opposite sides of said tube, and bending said portions into an arcuate shape.

2. The method of manufacturing an axle housing which consists in shearing a piece of metal stock at one end, forming an offset in the sheared end thereof, forming the unsheared portion of said stock into a tube, thereby placing the portions of said stock 75 adjacent said shear on diametrically opposite sides of said tube, and simultaneously bending said portions into an arcuate shape and forming flanges on the edges thereof.

3. The method of manufacturing an axle housing which consists in shearing a piece of sheet metal stock longitudinally at one end, forming an offset in the sheared end portion thereof, bending the unsheared end of said stock longitudinally into a channel shape, thereby initially spreading the portions of 85 said stock adjacent the shear, bending the edges of the channel part together so as to form a tube at the unsheared end of said stock and to position the spread portions on opposite side of said tube, and bending 90 said spread portions into an arcuate shape thereafter.

4. The method of manufacturing an axle housing which consists in shearing a piece of sheet metal stock longitudinally at one end, 100 forming an offset in the sheared end portion thereof, bending the unsheared end of stock longitudinally into a channel shape, thereby initially spreading the portions of said stock adjacent the shear, bending the edges of the 105 channel part together so as to form a tube at the unsheared end of said stock, and to position the spread portions on opposite side of said tube, welding said edges, and bending 110 said spread portions into an arcuate shape thereafter.

5. The method of manufacturing a tubular article having an enlarged end portion of substantially arcuate shape, the axes of the tubular and enlarged end portions being substantially 115 normal to each other, which consists in shearing a piece of sheet metal stock longitudinally at one end, bending the sheared end portion of the stock at an inclination to the plane of the unsheared portion, forming the unsheared portion of said sheet into a tubular shape and simultaneously spreading apart the inclined portions of said sheet so as to position 120 said spread portions on diametrically opposite sides of said unsheared tubular portion, and forming said inclined portions into arcuate shape.

6. The method of manufacturing an axle housing including an axle receiving sleeve and a differential casing which consists in shear- 130

ing one end of a planular piece of stock so as to provide a pair of prongs, forming the unsheared end of said stock into a tubular sleeve and positioning one of said prongs on each side thereof, and forming said prongs into an arcuate shape so as to provide one section of the differential casing.

7. The method of manufacturing a rear axle housing which consists in shearing the 10 end of a substantially rectangular piece of sheet metal stock so as to provide adjacent prongs, displacing said prongs from the plane of the unsheared end of said stock, bending the unsheared end of said stock into a tubular 15 shape and thereby spreading said prongs substantially 180° apart, and bending said prongs into arcuate shape.

8. The method of manufacturing a rear axle housing which consists in shearing the 20 end of a substantially rectangular piece of sheet metal stock so as to provide adjacent prongs, displacing said prongs from the plane of the unsheared end of said stock, bending the unsheared end of said stock into a tubular 25 shape and thereby spreading said prongs substantially 180° apart, and simultaneously bending said prongs into arcuate shape and forming side flanges thereon.

9. The method of forming an axle housing 30 assembly including spaced axle receiving sleeves and an intermediate casing which consists in shearing one end of each of a pair of planular pieces of stock so as to provide a pair of prongs on each piece of stock, 35 forming the unsheared ends of said stock into tubular sleeves and positioning one prong on each side of said sleeves, forming said prongs into an arcuate shape so as to provide one section of the differential casing on each 40 sleeve and securing said differential casing sections together.

10. The method of forming an axle housing assembly including spaced axle receiving sleeves and an intermediate casing which consists in shearing one end of each of a pair of planular pieces of stock so as to provide a pair of prongs on each piece of stock, forming the unsheared ends of said stock into tubular sleeves and positioning one prong on 45 each side of said sleeves, forming the pair of prongs with each sleeve substantially to semi-cylindrical shape so as to provide a half-section of the differential casing on each sleeve, bending the end portions of the differential casing sections inwardly, placing 50 rings adjacent the inwardly turning end portions of said half differential casing sections, and securing said inwardly turning end portions to respectively opposite segments of said rings.

DAVID A. WALLACE.
